Unsaturated iron binding capacity of transferrin, a serum protein, is determined by adding an iron solution containing a known quantity of excess iron to the serum to saturate the iron binding capacity of the serum transferrin, removing the remaining surplus iron with an absorbent and making a colorimetric determination by causing iron to be released from transferrin under an acidic condition. Since the iron solution is unstable in alkaline zone, it is stabilized by forming it into nitrilotriacetic acid iron chelates. The stability of iron chelates of sodium bathophenanthroline sulfonate is greater than that of nitrilotriacetic acid. This fact is utilized, and the surplus quantity of nitrilotriacetic acid chelates remaining after the saturation of the iron binding capacity of transferrin is measured by using sodium bathophenanthroline sulfonate. The sodium bathophenanthroline sulfonate iron chelates have maximum absorbance at the wavelength of 535 nm, and Beer's law holds for an iron concentration range up to 600 mg/100 ml.

METHOD OF DETERMINING UNSATURATED IRON BINDING CAPACITY IN SERUM

The present invention relates to a method of determining the unsaturated iron binding capacity in serum and, more particularly, to a method of readily and exactly determining the unsaturated iron binding capacity of the serum transferrin.

The clinical significance of blood iron was made clear by Heilmeyer (in 1937). Of the total quantity of iron contained in the adult body, 65 percent is present in red corpuscles as hemoglobin component (red corpuscle iron), and about 30 percent is stored in liver, pancreas, marrow of bones and kidney (stored iron). While iron contained in blood (blood iron) is very slight in quantity, no greater than mere 0.1 percent (3 to 5 milligrams), the quantity of iron getting into and out of blood through this blood iron is as great as 30 milligrams or more per day. This 25 to 30 milligrams of iron is utilized for the production of hemoglobin in the marrow of bones, so that it may be said that the blood iron maintains the blood producing function of the marrow.

In the serum the blood iron is bound to transferrin which belongs to β -globulin. Its normal content is 90 to 150 mg/100 ml for men and 80 to 120 mg/100 ml for women. The serum is capable of binding iron up to 300 to 360 mg/100 ml. This total capacity is termed total iron binding capacity, and the difference between the total iron binding capacity and the actual blood iron content is termed unsaturated iron binding capacity.

The determination of the total iron binding capacity and unsaturated iron binding capacity is utilized in the classification of various anemic diseases and in the determination and diagnoses of liver diseases and acute and chronic infectious diseases.

If the determination of the total iron binding capacity and unsaturated iron binding capacity is done along with the determination of the content of the blood iron, the diagnoses of various diseases stemming from abnormal iron metabolism can be done more precisely.

Major prior-art methods of determining the unsaturated iron binding capacity are as follows;

1. Magnesium carbonate method

This method consists of adding an excess iron solution, for instance a ferric chloride solution, to the serum to saturate the iron binding capacity of transferrin in the serum, subsequently removing surplus iron with magnesium carbonate, removing protein, thereafter estimating total iron binding capacity through a colorimetric process, and then subtracting the separately determined iron content value from the total iron binding capacity value, thereby determining the unsaturated iron binding capacity.

2. Peters method

This method consists of adding a ferric ammonium cyanate solution to the serum to saturate the iron binding capacity of the serum transferrin, then removing the surplus iron with a cation-exchange resin, and after the removal of protein determining the unsaturated iron binding capacity in the same way as mentioned above.

3. RI method

This method consists of adding a predetermined quantity of excess radioactive isotope Fe59 and iron to the serum to saturate the iron binding capacity of the serum transferrin, causing the residual surplus iron to

be absorbed in a resin sponge and measuring the radioactivity of the absorbed iron.

Of the above prior-art methods, the first two involve many operation steps and are very tedious. The last method requires special equipment and uses expensive reagents, so that it is difficult to be carried out in the usual examination room.

To solve the above problems encountered in the prior-art methods, it has been proposed to directly determine the unsaturated iron binding capacity by using a tris hydrochloric acid buffer (1.0 M, pH being 8.1), a standard iron solution (prepared by using ferrous ammonium sulfate and containing 500 mg/100 ml of iron and also used by adding 0.5 mg/100 ml of ascorbic acid) and 0.5 percent of a bathophenanthroline sulfonate solution. However, the above salt of iron is unstable and forms hydroxides of iron in alkaline liquid. Therefore, it is dissolved in an acidic solution, to which an alkaline buffer is subsequently added for color development and colorimetric determination, so that operation is involved.

An object of the present invention is to provide a method of speedily determining the unsaturated iron binding capacity of transferrin with a reduced number of operational steps.

Another object of the invention is to provide a method of determining the unsaturated iron binding capacity of transferrin with high accuracy and which enables one to obtain satisfactory reproducibility.

A further object of the invention is to provide a reagent (II)-BPT in the determination of unsaturated iron binding capacity of transferrin and one capable of preservation for a long time.

The above and other objects, features and advantages of the invention will appear more fully from the following description.

FIG. 1 is a graph showing an absorptive spectral of Fe (II)- BPT complex,

FIG. 2 is a graph showing the effect of pH on unsaturated iron binding capacity value,

FIG. 3 is a graph showing a relationship of rate of color development to time and temperature, and

FIG. 4 is a graph showing the calibrating curves representing the effect of Fe buffer solutions.

According to this invention there is provided a method of determining unsaturated iron binding capacity of transferrin by adding an iron solution containing a known quantity of excess iron to the serum to saturate the iron binding capacity of the serum transferrin and measuring the remaining surplus iron.

To carry out the above method, the problem has been studied of whether or not the number of operation

steps may be reduced by adding a standard iron solution to a tris hydrochloric acid buffer. It has been found that it is best to establish the standard iron solution in the form of iron chelate compound in order to preserve the solution in the tris hydrochloric acid buffer for a long time.

As the chelating agent there may be used ethylenediamine tetraacetic acid (EDTA), bathophenanthroline sulfonate (BPT), tripyridyl-s-triadine (TPTZ) and nitrilotriacetic acid (NTA). These substances can bind iron to form the so-called iron chelate compound, but their force of binding iron is different in the following way;

BPT > EDTA > NTA > TPTZ

It constitutes the principle underlying the invention that the unsaturated iron binding capacity of serum is determined by preparing a standard solution by dissolving an iron chelate compound in water, adding a predetermined quantity of sample serum to the standard solution and measuring the difference of absorbance before and after the addition of the serum.

More particularly, according to the invention a tris hydrochloric acid buffer containing the iron chelate compound is added to the serum to saturate the iron binding capacity of the serum transferrin, the surplus iron not bound to transferrin is removed, ascorbic acid is added, followed by the addition of bathophenanthroline sulfonate for colorimetric determination.

At this time, if the iron chelate compound is based on BPT or EDTA, the transferrin in the serum cannot derive iron from the chelates since the bond in the chelates is too strong. On the other hand, NTA and TPTZ have less strong iron binding forces than those of BPT and EDTA, so that transferrin can take up a requisite quantity of iron from the iron chelate compound based on NTA or TPTZ. TPTZ-Fe compound, however, is unstable in the tris hydrochloric acid buffer, so that it is not suited for practical use. From these grounds, it has been recognized that the NTA-Fe compound is suitable for use.

Considering another aspect, the unsaturated iron binding capacity of serum differs with pH. To examine the effect of pH the unsaturated iron binding capacity has been measured of transferrin in the same serum with the pH adjusted to various values by using M-tris hydrochloric acid buffer for a pH range between 7 and 9 and M-glycine sodium hydroxide buffer for a pH range between 9 and 11. The conclusion is reached that a highly unsaturated iron binding capacity can be maintained within a pH range between 8.4 and 8.7, as will be described hereinafter in connection with FIG. 2.

EXAMPLE

Preparation of reagents

Nitrilotriacetic acid iron buffer:

121.14 grams of tris (hydroxymethyl) aminomethane was dissolved in 800 millilitres of distilled water, and 0.08 gram of nitrilotriacetic acid and then 0.0117 gram of ferrous ammonium sulfate were added to and dissolved in the resultant solution. Then, the pH of the obtained solution was adjusted with 6N-hydrochloric acid. Then, distilled water was added to the resultant solution to adjust the total volume to 1,000 milliliters. The concentration of iron in the final solution is 166.7 mg/100 ml.

Nitrilotriacetic acid buffer:

It was prepared in the same way as the aforementioned and has the same composition as the aforementioned nitriloacetic acid iron buffer except for the fact that ferrous ammonium sulfate was not added.

Bathophenanthroline sulfonate solution:

It was prepared by dissolving 0.5 gram of sodium bathophenanthroline sulfonate in distilled water such that the total volume was 100 millilitres.

Reducing agent:

A small quantity of sodium ascorbate was used as the reducing agent.

The apparatus used for the preparation of the reagents and for the operation were all deironated.

Operation

Four test tubes A, B, C and D were prepared. 1.5 millilitres of nitrilotriacetic acid iron buffer was poured into each of the test tubes A, B and C, while 1.5 millilitres of nitriloacetic acid buffer was poured into the test tube D. Then, 10 milligrams of the reducing agent was poured into each test tube to produce each blend solution. Then, 0.5 millilitre of sample serum was poured into each of sample serum test tube A and serum blank test tube B, while 0.5 millilitre of distilled water was poured into each of standard iron solution test tube C and reagent blank test tube D. After leaving these tubes for 10 minutes, 0.05 millilitre of sodium bathophenanthroline sulfonate solution was poured into each of the tubes A, C and D, while 0.05 millilitre of distilled water was poured into the remaining tube B. After sufficiently stirring the individual resultant liquids and then leaving them at room temperature for 20 minutes, the absorbance of the samples, in the individual test tubes at the wavelength of 535 nm was measured with a spectrophotometer by using water as a reference.

By so doing, the unsaturated iron binding capacity (UIBC) of the serum can be determined from an equation

$$UIBC (\mu\text{g}/100\text{ml}) = 500 - \frac{E_A - E_B -}{E_C - E_D} \times 500$$

where E_A , E_B , E_C and E_D are values of the absorbance of the samples in the respective test tubes.

Absorbance curve

Sodium bathophenanthroline sulfonate iron chelates develop red color in alkaline solution, and FIG. 1 shows the resultant absorbance spectra in a wavelength range between 400 and 600 nm. Maximum absorbance was recognized at the wavelength of 535 nm. In the subsequent experiments the determination of the absorbance was made only for this wavelength.

Effect of pH on unsaturated iron binding capacity value of the serum

FIG. 2 shows the results of measurements of the unsaturated iron binding capacity value using M-tris hydrochloric acid buffer for a pH range between 7 and 9 and M-glycine sodium hydroxide buffer for a pH range between 9 and 11. As is shown, a substantially constant maximum value was obtained within a pH range between 8.4 and 8.7.

Relationship of rate of color development to time and temperature

As shown in FIG. 3, at temperatures about room temperature (20°C) the absorbance of both sample serum and standard iron solution settled to respective steady values in about 5 minutes. At temperatures of 15°C the time required until the settling was extended, particularly for the sample serum is about 15 minutes.

Effect of time for the action of serum on nitrilotriacetic acid iron buffer and sodium ascorbate on the unsaturated iron binding capacity value

Time until the serum transferrin was saturated with iron by deriving and binding with iron from the nitrilotriacetic acid iron buffer was determined. The unsaturated iron binding capacity was settled to a constant value after the sample had been left for 5 minutes.

Relationship between absorbance and Fe concentration in nitrilotriacetic acid iron buffer

A calibration curve was produced with the final Fe content adjusted to 0, 100, 200, 300, 400 and 500mg/100 ml for each nitrilotriacetic acid iron buffer and by using reagent blank as reference. The curve obtained was straight up to 500mg/100 ml and passed the origin, as shown at plot 1 in FIG. 4. Also, the absorbance was measured in the same way up to the Fe content of 500mg/100 ml in the nitrilotriacetic acid iron buffer but using a nitrilotriacetic acid buffer containing serum as reference. In this case, a straight plot parallel to plot 1 but lower than it by the absorbance value corresponding to the unsaturated iron binding capacity of the serum (in this case 220mg/100 ml) was obtained, as shown at plot 2. It is to be noted that this plot shows absorbance of 0.005 to 0.01 for Fe contents of 100 and 200mg/100 ml. This is due to the pink coloring of the iron in the transferrin. This is re-confirmed from the fact that the absorbance of plot 3 obtained in case of adding only nitrilotriacetic acid iron buffer and reducing agent but not adding sodium bathophenanthroline sulfonate to the serum increases linearly from zero Fe content to the saturation point of 220g/100 ml, and then it remains unchanged for greater Fe contents. Results of determination of unsaturated iron binding capacity value in human serum

Unsatratd iron binding capacity value for 32 human serum samples was determined by the method according to the invention and also through calculation based on the Peter method and magnesium carbonate method. Table (I) lists the analytical results. Excellent results were found to be obtained by the method according to the invention, with the co-relation coefficient and regression line with respect to the value (y) according to the Peter method being respectively 0.98 and (y) = $0.97 + 10.5$ and those with respect to the value (y') according to the magnesium carbonate method being respectively 0.90 and (y') = $0.98 + 10.4$

the recovery of iron by adding 10, 30 and 50mg/100 ml of Fe(II) to each sample. Table (II) shows the results of the experiments. The recovery was 89.2 to 103.7 percent and 94.4 percent in the average.

Table (II)

Sample No.	Fe added (μg/100ml)	Recovery of iron added to serum	
		Fe found (μg/100ml)	Recovery (%)
1	0	195.05	—
	10	184.68	103.7
	30	168.08	89.9
	50	150.44	89.2
2	0	216.65	—
	10	207.25	94.0
	30	188.61	93.5
	50	168.48	96.3

20 Effect of bilirubin in human serum

The effect of bilirubin added to the human serum of up to 40mg/100 ml upon the unsaturated iron binding capacity value was examined. The value was gradually increased with increases in the bilirubin content of up to 20/mg/100 ml, and a maximum positive error of difference of about 20mg/100 ml resulted. As the bilirubin content was increased beyond 20mg/100 ml the value began to be lowered and approached the initial value.

30 As has been described in the foregoing, the method according to the invention permits a simple and speedy operation. Also, according to the invention it is possible to obtain satisfactory precision of determination and recovery. Further, the correlation with the prior art methods using iron absorbants is substantially satisfactory. Thus, the method according to the invention is thought to be suitable as practical analytic method for the determination of the unsaturated iron binding capacity in serum.

Table (I)

Sample Number	Analytical results of UIBC value in human serum			
	Proposed method	Peters method	MgCO ₃ method	(μg/100ml)

16	239.5	239.9	241.6	32

Reproducibility

The same human serum sample (with unsaturated iron binding capacity value of 1.89mg/100 ml) was analyzed ten times, and the variation factor was found to be 1.3 percent.

Recovery

Two human serum samples were used experimenting

What we claim is:

1. A method of determining the unsaturated iron binding capacity of transferrin in serum comprising the steps of:
  - preparing a standard solution of iron chelate in which a known amount of iron is bound with nitrilotriacetic acid by using a buffer solution of pH 8.4 to 8.6;

adding the said standard iron solution to a sample serum in order to saturate the iron binding capacity of transferrin in the said serum; reducing the excessive iron remaining unbound with transferrin by adding a salt of ascorbic acid to the said saturated solution; developing a color by adding sodium bathophenanthroline to the said reduced solution, and determining the absorbance of the said colored solution.

2. The method as defined in claim 1, wherein said standard solution contains a small quantity of sodium ascorbate to serve as a reducing agent.

3. A method of determining the unsaturated iron binding capacity of serum comprising the steps of: preparing four test tubes; preparing a sample serum by pouring 1.5 millilitres of a nitrilotriacetic acid buffer, 10 milligrams of a reducing agent, 0.5 millilitre of the serum and 0.05 millilitre of sodium bathophenanthroline sulfonate into a first one of said test tubes; preparing a serum blank by pouring 1.5 millilitres of a nitrilotriacetic acid iron buffer, 10 milligrams of said reducing agent, 0.5 millilitre of said serum and 0.05 millilitre

of distilled water into a second one of said test tubes; preparing a standard iron solution by pouring 1.5 millilitres of said nitrilotriacetic acid iron buffer, 10 milligrams of said reducing agent, 0.5 millilitre of distilled water and 0.05 millilitre of a sodium bathophenanthroline sulfonate solution into a third one of said test tubes; preparing a reagent blank by pouring 1.5 millilitres of said nitrilotriacetic acid buffer, 10 milligrams of said reducing agent, 0.5 millilitre of distilled water and 0.05 millilitre of said sodium bathophenanthroline sulfonate solution into the last one of said test tubes; determining the absorbance at the wavelength of 535 nm of the respective samples in said test tubes by using water as reference; and calculating the value of the unsaturated iron binding capacity from the values of the absorbance of said respective sample.

4. A composition for determining the unsaturated iron binding capacity in serum comprising in proportion 1.5 millilitres of a nitrilotriacetic acid iron buffer, 10 milligrams of a salt of ascorbic acid, 0.5 millilitres of distilled water and 0.05 millilitres of a sodium bathophenanthroline sulfonate solution.
